EX

OR D 15.072

No. 15,072 June 17, 1884

N° 293

UNITED STATES PATENT OFFICE.

ADOLPH G. HOESTATTER, OF NEW YORK, N. Y.

DESIGN FOR A CHAIR-FRAME.

SPECIFICATION forming part of Design No. 15,072, dated June 17, 1884.

Application filed April 3, 1884. Term of patent 5 years.

To all whom it may concern:

Be it known that I, ADOLPH G. HOESTATTER, of the city, county, and State of New York, have invented a new and original Design for the 5 Frame of a Conversation Chair; and I do hereby declare that the following is a full and exact description thereof.

The character of my design is clearly illustrated in the accompanying photograph, to 10 which reference is made as forming a part of this specification.

It consists in the configuration of a double chair-frame, the form of whose seat-support is produced by the intersection centrally at 15 about a right angle of two bars of equal length, whose opposite angles are included each in a quadrilateral, the two inner sides of which are bounded by the sides of said angles, and whose outer sides are bounded by bars parallel with 20 said sides, the form of the back of the frame being produced by the intersection of a top rail having the form of a double reverse curve with uprights projecting at a right angle with the plane of the intersecting seat-bars, first, at 25 the point of intersection of said bars; second, at the two opposite ends of one of them; and, third, at the extreme outer angles of the two squares.

In the accompanying photographic illustration, A A' are the middle bars of the seat-frame, which intersect each other centrally at a right angle; and A² A³ A⁴ A⁵, its outer end bars, fitted to the ends of the middle bars at a right angle thereto and to each other. The form of the

frame is substantially that of two rectangular 35 equilateral squares produced upon and between the two intersecting lines A A', so as to embrace in each one of the opposite angles, B B', formed by said lines.

C C' are the uprights for the back, projecting at a right angle from the intersection of the two middle bars, A A', at each end of one of said bars A, and at each of the two outer ends of the frame. The contour of the frame is completed by the top plate, D, and parallel 45 middle rail, E, for the back, each having the form of a reverse curve extending from the one outer upright, C, to the other, and touching in its sweep each of the intermediate uprights.

I claim as my invention-- 50

The design for a chair-frame, which consists of two equilateral open squares produced upon the opposite sides of two equal intersecting lines, in combination with a double reverse curve produced by a rail or strip carried above 55 the two squares in a plane parallel with its intersecting lines, and in position to extend over their point of intersection, over the angles at each end of one of said lines, and over the angles at the two ends of the connected squares, 60 substantially as shown and described.

In testimony whereof I have signed my name to this specification in the presence of two subscribing witnesses,

ADOLPH G. HOESTATTER.

Witnesses:

A. B. MOORE.

G. H. SPENCER.
